UNITED STATES PATENT OFFICE

2,550,800

PARING HEAD FOR APPLE PARING MACHINES

Ronald A. Ganze, Marion, N. Y., assignor to Comstock Canning Corporation, Newark, N. Y., a corporation of New York

Application May 28, 1948, Serial No. 29,737

9 Claims. (Cl. 146—43)

1

The present invention relates to a paring head or knife head for use in apple paring machines and similar machines. It has for its broad object to provide a simple, efficient and durable head that will be automatically self adjusting in its cutting, so that a thinner peeling will be automatically cut from an apple of smaller diameter than from one of larger diameter. This results in less waste than heretofore, and in a considerable saving in usable pulp.

Apples can be graded according to size, if desired, but this involves an extra operation and extra expense. If they are not graded, and if they are delivered in random sizes to a paring machine of the kind heretofore customarily used in an apple processing factory, the paring machine will cut substantially the same thickness of paring from a small apple as from a large apple, which is wasteful of the pulp of small apples because in actual practice it is found that, with certain varieties of apples, it is sufficient to take a somewhat thinner peel or paring from smaller apples than is required from larger apples. The present invention aims to adjust the thickness of peel automatically to the size of the apple, taking a thinner peel from a smaller apple and a thicker peel from a larger apple.

Another object of the invention is to accomplish the above purposes while additionally supplying the further function of rendering the throat of the paring head self clearing as to clogs that have always been a problem in paring machines.

A further object is to simplify the assembly and disassembly of the paring head or knife arm.

These and other desirable objects are accomplished by the construction disclosed as an illustrative embodiment of the invention in the following description and in the accompanying drawings forming a part hereof, in which:

Fig. 1 is a front view of an apple paring machine of a conventional type, to which has been applied a paring head unit constructed in accordance with and illustrating one embodiment of the present invention;

Fig. 2 is a detail elevation of the paring head and its mounting appearing in Fig. 1, but at a different point in the orbit traveled by the knife, which latter is here shown operating upon an apple of small diameter;

Fig. 3 is a view of the knife arm alone, viewed from the side toward the apple;

Fig. 4 is a view similar to Fig. 2 but showing the positions of the parts when the knife is

2

working upon an apple of relatively large diameter;

Fig. 5 is a view of the knife arm alone, viewed from the side opposite to that shown in Fig. 3; and

Fig. 6 is a face view of the carriage or support and actuating gear that impart the desired movement of the paring head around the apple, the knife arm and its guard arm being in transverse section on the line 6—6 of Fig. 1.

The same reference numerals throughout the several views indicate the same parts.

The general construction of the paring machine as shown in Figs. 1 and 6 (other than the paring head itself) constitutes no part of the present invention. The parts (other than the paring head) shown in these Figs. 1 and 6 are conventional parts well known in the art, and are here illustrated in a fragmentary way only for the purpose of explaining the environment and general actuation of the paring head of the present invention. These conventional parts will therefore be described first, and only briefly.

The paring machine, mounted on an outer frame 10, carries an inner mounting frame 12 upon which the moving parts are supported, including a main shaft 14, a cam wheel 16 driven thereby, and gearing 18 that rotates the vertical fork spindle 20 terminating at its lower end in a fork (dotted lines) 22 upon which the apples A or similar fruits or work pieces are impaled by a feeding cup 24. In succession and in proper timed relation the knife or cutting head 26 rises and pares the fruit, after the cup 24 has swung out of the way; the corer 28 moves up and cuts out the core and brings the fruit down to the forked doffer 30; and finally the paring knife returns to its lower full line position. Some of the other details of construction of a machine of this kind are disclosed, for example, in United States Patent 1,615,914, granted February 1, 1927, on the application of J. W. Pease.

These just described cycles of movement involve a vertically reciprocating carriage frame 32 raised by a pin 34 on cam wheel 16 engaging a cam 36 on the frame, which latter is counterbalanced by a spring 38 and guided on frame 12. Secured to frame 32 is a bracket 40 (Figs. 2 and 4) terminating in yoke arms 42 which constitutes the immediate support and carriage upon which the cutting head 26 is mounted. A sleeve 44 secured in the yoke arms by set screws 46 forms a bearing for a rock shaft 48. Fixed to what may be termed the rear projecting end of this shaft by a set screw 50 is a yoke 52 the arms 54 of

which enclose a convex fulcrum bearing or fulcrum seat 56 and a relatively restricted slot or opening 58 leading from the fulcrum seat. Fixed to the other or forward projecting end of said shaft 48 through the medium of a collar 60 and set screw 62 is a guide yoke 64.

A knife arm 66 of the conformation shown, through a threaded outer end 68 and lock nut 70, carries the cutting head 26, earlier mentioned, which, in turn, has affixed thereto by adjusting screws 72 the slotted, inclined knife 74, much as usual. The peelings P from the knife in action pass through a throat 76 closed at only one side. Acting in conjunction with the knife is a guard 78 further defining the throat 76 and regarding which there will be further description.

The rear end of knife arm 66 has a flat bearing portion 80 resting against the convex fulcrum seat 56 in the yoke arms 58, and beyond the latter the terminal of the arm has fixed thereto an arm 82. A contracting coil spring 84 engaged with this arm and reacting against an extension 86 on the end of guide yoke 64 actuates the knife arm to press the knife 74 into paring engagement with the apple or other work piece A on fork 22. The limit of this movement of the arm and knife is defined by the inner end of the guide yoke 64.

An extension of guide yoke 64 beyond rock shaft 44 carries two lugs 88 (Figs. 2 and 6) in triangular relationship to an intermediate roller 90. Lugs 88 are adapted to travel, with the motion of carriage frame 32, upon a track 92 (Fig. 6) on an extension of fixed frame 12 while roller 90 travels similarly on a track 94 on the same element. When the carriage frame 32 is in its lowermost position, as shown in full lines in Figs. 1 and 6, the arm 66 and knife are in the inoperative full line position of those figures. As the carriage rises, a lug 88 strikes a cam face 96 on track 92 and revolves the knife arm unit on the rock shaft 48. In the meantime the knife meets the bud end of the apple A and starts paring. The cam action causes it to swing in an orbit following the contour of the apple or other work piece. The roller 90 rides into a depressed cam 98 in the track 94 for such motion as shown in dotted lines in Fig. 6, at which point the knife is in the dotted line position of Fig. 1 midway of the apple and of its own travel. The rest of the semi-circular orbit is traversed as the roller 90 rides out of the depression 98 and the other lug 88 rides down a cam surface 100 on the track 92 and rides along the latter as shown in the upper dotted line position in Fig. 6.

Returning to the cutting head 26 and the knife arm 66, the guard 78 which rides on the apple or work piece in spaced relation to the edge of knife 74 and which determines the depth of cut of the knife, is carried by and clamped between a short arm 102 on a yoke 104 and a spring clip 106 held by a screw 108 threaded into this yoke 104. The latter is pivoted to the head 26 at 110 to rock in a limited fashion thereon. A long arm 112 integral with the short arm 102 extends rightwardly from the yoke 104 when viewed as in Fig. 2, and passes under knife arm 66 within guide yoke 64. Near its right end, the arm 112 is provided with a contact finger 114 adjustably held on the arm by a screw 116 threaded into the arm through a slot in the contact finger. This contact finger bears on the member 44.

It will be seen from the foregoing that the guard 78 may rock on the yoke pivot 110 toward and from the knife edge. The resulting function is as follows:

The spring 84 constantly tends to swing the paring knife 74 in a direction toward the center of the apple A, the limit of such swinging motion being determined by contact of the guard 78 with the surface of the apple. This bodily swinging movement toward the center of the apple occurs about the fulcrum part 56 and 80 as a center. On a relatively small apple, as indicated diagrammatically in Fig. 2, the parts can swing until the rod or bar 66 of the apple paring head lies relatively close to the member 44, and this member 44, acting on the contact finger 114 of the arm 112, will swing the guard member 78 on the pivot 110 to a position relatively close to the cutting edge of the knife 74, thus producing a relatively thin cut or peel, as indicated in Fig. 2.

On the other hand, when the cutting head is operating against a larger apple, as illustrated diagrammatically in Fig. 4, then the cutting head 20 is unable to swing so close to the center of the 25 apple, and the size of the apple will keep the rod 66 from swinging so close to the member 44. The greater space between the rod 66 and the member 44 allows the lever arm 112 to swing farther away 30 from the rod 66, as seen from a comparison of Fig. 4 with Fig. 2, and the swinging of the lever arm 112 away from the rod 66 results in swinging the guard member 78 in a clockwise direction about its pivot 110, which moves the effective or 35 lefthand edge of the guard member 78 farther out to a position farther behind the cutting edge of the knife 74, thus producing a thicker cut or peel, as indicated in Fig. 4 when compared with Fig. 2. In this way, the thickness of the peel or cut taken 40 by the paring head is a direct function of the diameter of the apple or other work piece being operated upon, a thicker peel being taken from a work piece of larger diameter and a thinner peel being taken from a work piece of smaller diameter.

The degree to which the thickness of cut will be varied by a given variation in diameter of the work, may be adjusted to some extent by loosening the screw 116 and moving the contact finger 45 114 rightwardly or leftwardly along the arm 112. The maximum thickness of the cut in any event, regardless of any excessive diameter of the apple, may be limited by a set screw 118 threaded through a lug 120 on the head member 26, which 50 screw 118 has an end which limits the clockwise motion of the arm 112 about its pivot 110.

In paring apples of all sizes as they normally come to the apple factory, the guard 78 is constantly, on successive operations, moving toward 55 and from the knife edge, so that the possibility of clogs occurring is remote.

The inner end of the guide slot in the yoke 64 furnishes an ultimate stop for both the guard arm and the knife arm, the latter through the 60 medium of the former.

To remove the knife arm with facility as well as to assemble it easily and quickly, a reduced portion 122 is formed thereon adjacent to the fulcrum bearing portion 80. By thrusting this reduced portion rearwardly and outwardly it is passed laterally through the restricted opening 58 in the bearing yoke and thence is passed through a corresponding slot 124 in the guide yoke 64. A reversal of these movements of course 65 70 assembles the parts. The tension spring 84, obviously, is first moved.

This automatic variation of the thickness of peel in accordance with the varying diameters of successive apples, is found in actual practice to 75 result in a considerable saving of usable pulp.

In an apple paring machine of the kind shown, for example, in Figs. 1 and 6, the apple spindle 20 revolves a definite number of revolutions during each cycle of swinging of the paring head through a half revolution or 180° from the position shown in full lines at the bottom of Fig. 6 to the position shown in dotted lines at the top of Fig. 6. But on an apple of larger diameter, the width of the cut made by the cutting knife during one revolution of the spindle should be greater than the width of the cut on a smaller diameter apple, because the circumferential distance (or rather the semi-circumference of the apple) to be covered by the successive cuts during successive revolutions of the spindle is greater on a larger diameter apple than on a smaller diameter apple. In order to make the cutting knife cut a wider cut, it is necessary to take a deeper cut in the apple. Yet if this same depth of cut is taken on an apple of smaller diameter, the cut made during one revolution of the apple spindle 20 overlaps the cut made during the previous revolution of the spindle to an unnecessarily great extent, thus wasting the pulp of the apple.

It is seen from the foregoing disclosure that the above-mentioned objects of the invention are admirably fulfilled. It is to be understood that the foregoing disclosure is given by way of illustrative example only, rather than by way of limitation, and that without departing from the invention, the details may be varied within the scope of the appended claims.

What is claimed is:

1. In a cutting head mechanism for paring machines, the combination with a carriage support and a spring actuated knife arm fulcrumed thereon to swing toward and from the work and carrying a knife holder and knife, of a guard pivoted on the holder in changing relationship to the knife edge, said guard being so mounted for movement relative to said edge as to recede from said edge for a deeper cut in response to pressure of contact with the work, and an extension on the guard reacting against the support at a location spaced from the fulcrum connection between said support and said knife arm to limit such recession more or less according to an advanced or retracted position of the knife arm and knife.

2. In a cutting head mechanism for paring machines, the combination with a support and a spring actuated knife arm fulcrumed thereon to swing toward and from the work and carrying a knife holder and a knife, of a guard pivoted on the holder for movement relative to the knife edge in a general direction toward and away from the center of the work being pared, said guard having a tendency to recede from such edge for a deeper cut in response to pressure of contact with the work, and means actuated by the knife arm for advancing the knife edge for a shallow cut as the knife arm moves a predetermined distance in the direction of the work, said means including a guard actuating arm operatively connected to said guard to oscillate said guard relative to said holder and extending in a general direction from said guard toward the fulcrum of said knife arm on said support and engaging said support at a point spaced from said fulcrum so that said guard actuating arm will be moved relative to said knife arm when said knife arm swings relative to said support on its fulcrum.

3. In a cutting head mechanism for paring machines, the combination with a support and a spring actuated knife arm fulcrumed thereon

to swing toward and from the work and carrying a knife holder and a knife, of a guard idly pivoted to the holder in changing relationship to the knife edge, said guard having a tendency to recede from such edge for a deeper cut in response to contact with the work, an arm extending from the guard and slidably reacting against the support for limiting such recession of the guard and also actuated by the knife arm to advance the guard toward the knife edge for a shallow cut as the knife arm moves a predetermined distance in the direction of the work, and a stop engaged by the knife arm through the medium of the guard arm for halting the last mentioned movement of both of said arms.

4. In a cutting head mechanism for paring machines, the combination with a carriage and a spring actuated knife arm fulcrumed thereon to swing toward and from the work and pivoted on the carriage to swing bodily laterally to follow the contour of the work, said arm carrying a knife holder and a knife, of a guard idly pivoted to the holder in changing relationship to the knife edge, said guard having a tendency to recede from such edge for a deeper cut in response to contact with the work, and being provided with an arm having a sliding contact with the carriage at a point remote from the fulcrum of the knife arm to limit such recession of the guard and also actuated by the knife arm to advance the guard toward the knife edge for a shallow cut as the knife arm moves a predetermined distance in the direction of the work, and a stop against which the knife arm tends to move the guard arm to limit the lighter cutting self adjustment of the guard and to arrest both arms when the knife is not in work.

5. In a cutting head mechanism for paring machines, the combination with a carriage embodying a yoke and a sleeve connecting the arms thereof, a shaft turning in the sleeve, a guide yoke fixed to one end of the shaft, and a seat member fixed to the other end, of a spring actuated knife arm fulcrumed on the seat member to swing within the guide yoke toward and from the work and to swing bodily laterally on the shaft to follow the contour of the work, said arm carrying a knife holder and a knife, and a guard idly pivoted on the holder in changing relationship to the knife edge, said guard having a tendency to recede from such edge for a deeper cut in response to contact with the work, and being provided with an arm also swinging within the guide yoke and having a sliding contact with the carriage yoke sleeve to limit such recession, the guide yoke also providing a stop against which the knife arm tends to move the guard arm to limit the lighter cutting self adjustment of the guard and to arrest both arms when the knife is not in work.

6. In a cutting head for paring machines, the combination of a support having a stop and a spring actuated knife arm fulcrumed on the support to swing toward and from its work and the stop and carrying a knife holder and a knife, and a guard element idly pivoted on the holder in changing relationship to the knife edge and independently reacting against the support, said guard element tending to recede from the knife edge in response to pressure of contact with the work piece to allow said knife to produce a deeper cut, and means operated by relative movement between said knife arm and said support for causing said guard element to advance toward the knife edge for a shallower cut.

7. A paring machine adapted to pare generally globular articles of different sizes and including a support, a knife arm, a knife blade carried by said knife arm, said knife arm being fulcrumed at one point on said support to swing in a direction to carry said knife blade in a general direction toward and away from the center of a globular article to be pared, and a spring tending to swing said knife arm to carry said knife blade toward said globular article, characterized by said knife blade toward said globular article, characterized by a knife guard pivotally mounted on said knife arm and having a guard portion lying adjacent said knife blade to contact with the article being pared and to control the depth to which said knife blade may penetrate said article, said knife guard also having an operating portion movable relative to said knife arm in response to movement of said knife arm relative to said support, thereby to move said guard portion relative to said knife blade to vary the depth of cut made by said knife blade in said article being pared, said operating portion of said knife guard bearing against said support at a second point spaced from the point at which said knife arm is fulcrumed and being operated by relative movement between said second point and said knife arm.

8. A construction in accordance with claim 7, in which said second point is between said knife blade and said point at which said knife arm is fulcrumed, and in which the pivotal mounting of said knife guard on said knife arm is between said second point and said guard portion of said knife guard.

9. A paring machine adapted to pare generally globular articles of different sizes and including

5
10
15

a support, a knife arm, a knife blade carried by said knife arm, said knife arm being fulcrumed at one point on said support to swing in a direction to carry said knife blade in a general direction toward and away from the center of a globular article to be pared, and a spring tending to swing said knife arm to carry said knife blade toward said globular article, characterized by guard means cooperating with said knife blade to control the depth of paring cut made by said blade, and means controlled by swinging movement of said knife arm on its fulcrum on said support for automatically shifting said guard means relative to said knife arm and blade in accordance with varying sizes of respective articles being pared to cut a thicker peel from an article of larger size and a thinner peel from an article of smaller size.

RONALD A. GANZE.
